CLAIM

The ornamental design for a lighting device, as shown and described.

DESCRIPTION

FIG. 1 is a top front perspective view of a lighting device with a connected strap according to one exemplary embodiment of the present design.

FIG. 2 is a bottom rear perspective view of the lighting device with the connected strap of FIG. 1.

FIG. 3 is a top front perspective view of the lighting device of FIG. 1

FIG. 4 is a bottom rear perspective view of the lighting device of FIG. 1.

FIG. 5 a front view the lighting device of FIG. 1.

FIG. 6 is a back view of the lighting device of FIG. 1.

FIG. 7 is a left side view of the lighting device of FIG. 1.

FIG. 8 is a right side view of the lighting device of FIG. 1.

FIG. 9 is a top view of the lighting device of FIG. 1; and, FIG. 10 is a bottom view of the lighting device of FIG. 1. The broken lines shown are provided for the purpose of illustrating environmental structure and form no part of the claimed design.

1 Claim, 10 Drawing Sheets---
